United States Patent Office

Des. 197,718
Patented Mar. 17, 1964

197,718

MEDALLION OR THE LIKE

Charles A. Reynolds, Washington, D.C., assignor to the United States of America as represented by the Secretary of the Army

Filed May 4, 1962, Ser. No. 69,986

Term of patent 14 years

(Cl. D29—19)

(Granted under Title 35, U.S. Code (1952), sec. 266)

Fig. 1.

Fig. 2.

FIG. 1 is a front view of a medallion or the like showing my new design; and

FIG. 2 is a side elevational view of the same.

The essential features of my design are shown in full lines.

The back of the medallion is plain and unornamented.

The invention described herein, if patented, may be manufactured and used by or for the Government for governmental purposes, without the payment to me of any royalty thereon.

I claim:

The ornamental design for a medallion or the like, as shown and described.
